UNITED STATES PATENT OFFICE.

FORÉE BAIN, OF LA GRANGE, ILLINOIS.

SHEET-METAL RECEPTACLE.

1,123,218.

Specification of Letters Patent.

Patented Jan. 5, 1915.

Application filed February 23, 1911. Serial No. 610,240. Renewed October 17, 1913. Serial No. 795,789.

To all whom it may concern:

Be it known that I, FORÉE BAIN, a citizen of the United States, residing at La Grange, in the county of Cook and State of Illinois, have invented certain new and useful Improvements in Sheet-Metal Receptacles, of which the following is a specification.

My invention relates to improvements in sheet metal receptacles, such as "wet" barrels, and the like; and one of the objects of my invention is to provide an improved means for joining the body and the head of such receptacles.

A further object of my invention is to provide an improved receptacle wherein the head and the body may be formed separately and subsequently secured together by means of a ring member, without the necessity of deforming or distorting either the body or the head member in the assembling operation, and whereby a rigid, strong, and tight structure is produced.

Other and further objects of my invention will become apparent to those skilled in the art from the following specification taken in conjunction with the accompanying drawing, wherein—

Figure 1 indicates in broken elevation a receptacle embodying my invention, one end thereof being shown in central vertical section; Fig. 2 represents in section fragments of a receptacle embodying my invention, the body and head with a clamping ring member ready for application thereto; Fig. 3 is a similar view showing the ring member applied to the body and head before the rolling operation; and Fig. 4 is a similar view showing the completed joint.

For purposes of clear disclosure of my invention, I have illustrated a barrel as a proper exemplification thereof, and in the structure shown 5 indicates a cylindrical body and 6 a disk-head of ordinary concavo-convex shape, each being formed of sheet metal. The head 6 has the usual rim-flange 7 at its outer edge, interiorly interfitting into the rim portion 5' of the body, so that its free edge is flush with the end edge of the body. It will be understood that where the receptacle is a barrel, both ends are made alike, but for purposes of definition directions will uniformly be referred to as they appear in Figs. 2 to 4, "upper" meaning toward the middle of the barrel, and "lower" meaning toward the end of the barrel.

The angle, 8, formed between the rim

portion 7 and the transverse web or disk of the head (which I will term the "rim-angle" of the head), preferably seats against a shoulder 9, formed in the peripheral wall of the body at the upper extremity of the rim portion 5' thereof, the shoulder being preferably formed by rolling, in the barrel body, an internal bead affording an exterior circumferential channel 10.

The U-shaped clamping ring 11 is made of suitable malleable metal, such as soft iron, or steel, to provide concentric exterior and interior limbs 12 and 13, separated by the annular groove or recess 14, as shown in Fig. 2, the outer limb being taller or deeper than the inner limb. The inner limb, 13, is preferably provided with an annular flange 15, inturned substantially at right angles to the limb, the juncture, 16, of the upper and exterior surfaces of the flange and limb respectively (which I will term the "bearing edge" of said inner limb) lying in a plane lower than the free edge 17 of the exterior limb 12.

At the bottom of the groove, 14, of the clamping ring, I preferably provide a small wire 18 of a ductile material softer than that of which the remainder of the structure is composed,—such as lead, solder, or the like,—so that it will be compressed or spread in the process of rolling the ring in place, to act as an auxiliary sealing means for the joint to be made.

Fig. 3 shows the members of the structure ready for final compression of the clamping ring to complete the joint, the rim portions 7 and 5' of the head any body lying in the groove 14 of the clamping ring with the lower edges of said rim portions resting on the wire 18 and with the bearing edge, 16, of the inner limb of the clamping ring, interfitting with the rim-angle 8 of the head, the free edge 17 of the exterior limb extending above the plane of said angle 8. In completing the joint, the parts are forced into the position shown in Fig. 4, as by a suitable rolling operation. The limbs of the ring are brought into intimate contact with the contiguous portions of the body and head structures throughout substantially their entire extent, and the free edge 17 of the exterior ring limb 11 is rolled over in a plane above the bearing edge 16 of the opposing limb 13 and forced into the groove 10 of the receptacle body to clamp the shoulder 9 of the body and the rim-angle

8 of the head against the bearing edge 16 of said inner limb, the pressure or compression line of said clamping effect being at an oblique angle substantially as indicated by 5 dotted line 20—20.

In the rolling operation, the internal flange 15 of the ring member serves as an abutment for an anvil or base-roll, so that the pressure roll may be applied against 10 the end 17 of the exterior limb to exert stress on the pressure line 20—20 to turn said edge into the groove 10 and to produce the desired compression of clamping action between the bearing edge 16 of the inner limb 15 and the free edge of the outer limb, without straining the head or rim flange. It is usually convenient and preferable to provide the channel or groove 10 in the receptacle body preliminarily to the assembling operation 20, and in such cases the subsequent assembling of the parts is effected without distortion or displacement of any portion of the barrel or head structures; but it will be apparent that when so desired, the groove 10 25 may be made at the time of, and incidentally to, the inturning of the free edge 17 of the clamping ring.

It will be observed that the joint is primarily made as a result of rolling the longer limb of the U-shaped clamping member over the edge of the shorter limb of said ring member, clamping similarly contorted portions of the body and head members in the angle formed between the edges of the longer and shorter limb members, but the joint is of course aided by the intimate contact of the parallel portions of the limb members with the contiguous cylindrical rim portions of the body and head, and by 30 the sealing effect of the ductile wire 18. By forming the joint with the outer limb member inrolled, it will be observed that the principal joining effect is secured at the rim-angle 8 normal to the head structure without 35 any distortion whatever of the head, said rim-angle being adequately supported by the clamping ring flange 15, so that neither in the rolling operation nor in use is it subject to any such strain as to render it liable 40 to rupture. Thus, by the arrangement of the inrolling of the longer outer limb over a bearing edge of the shorter limb, entering 45 the normal angle of the head, I am enabled to secure substantially a right-angle joint without imposing undue strain on any portion 50 of the sheet metal which would render it liable to rupture.

The clamping ring 11 is preferably so formed that its lower or standing edge provides 60 an end bearing surface alining with only the inner limb 13, as indicated at 21, Fig. 4. To this end, the lower portion of the clamping ring is chamfered as at 22, the object being so to locate the end bearing of 65 the ring below the inner limb 13 that the

weight of the barrel, or shocks imparted to the lower edge of the ring, tends to lift the inner limb 13, with a resultant tendency to tighten the joint between the upper edges of the ring limbs rather than to spring them apart. 70

While I have herein described only a single embodiment of my invention, it will be evident that the illustrative exemplification is susceptible of changes without departure from the spirit of the invention and within the scope of the appended claims. 75

What I claim is:

1. A receptacle comprising a head, a body, and a clamping member, said clamping member having substantially parallel concentric inner and outer limbs between which portions of said body and head member are inclosed, the edge of one limb being laterally deflected toward and above the upper bearing edge of the other limb, to clamp between said edges portions of the head and body, and portions of said head and body clamped between said edges being compressed. 80

2. In a metallic receptacle, the combination with a body and a flanged head interfitting to provide a rim, of a clamping member having parallel concentric limbs embracing said rim, the inner limb of the clamping member having its upper bearing edge fitting in the rim angle of the head, and the outer limb having its free edge inwardly deflected in a plane above the head, to clamp said rim-angle and a portion of the body against the bearing edge of said inner limb. 95

3. In a metallic receptacle, the combination with a body and a flanged head presenting concentrically interfitting rim portions, of a clamping ring having concentric limbs substantially embracing said rim portions, the inner limb of said ring having its end inturned to form a substantially right-angle flange with its bearing edge engaging the head at the rim-angle thereof, the outer limb of said ring having its free edge inwardly deflected in a plane above the head to clamp the rim-angle and a portion of the body against the bearing edge of the said inner limb. 100

4. In a metallic receptacle, the combination of a body member exteriorly grooved to provide an internal shoulder, a head member flanged and interfitting in said bottom member and bottoming against said shoulder, and a clamping member having concentric limbs embracing the interfitting rim portions of the head and body, and having parts respectively overlying the shoulder of the body and underlying the rim-angle of the head to effect a joint therebetween. 115

5. In a metallic receptacle, the combination of a body member provided with an internal shoulder and a corresponding exter- 120 125 130

- nal groove formed in its wall near the end thereof, a head member having an interfitting concentric rim bottoming against said internal shoulder, and a U-shaped clamping member one limb thereof within said rim portion and the other limb having a portion thereof lying within said groove to clamp the parts together.
6. A receptacle comprising a head, a body, and a clamping member, said member having substantially parallel inner and outer limbs between which portions of said head and body are inclosed, the edge of the outer limb being inturned toward and above the upper bearing edge of the inner rim to clamp said parts together.
7. A receptacle comprising a head, a body, and a clamping member, said member having substantially parallel shorter and longer limbs between which portions of said head and body are inclosed, the edge of the longer limb being turned toward and above the upper bearing edge of the shorter limb, to clamp said parts together the body and head
- parts being compressed between said limb-edges, and the free standing edge of the clamping member being circumferentially chamfered so as to leave the weight-bearing surface only under said shorter limb.
8. A receptacle comprising a head, a one piece circumferentially continuous body, and a clamping member, said head and body having interfitting cylindrical portions and said clamping member having integral concentric limbs spaced apart by an annular recess in which said cylindrical portions are received, said inner limb having a bearing edge at a point spaced from the bottom of said recess, and the salient edge of said outer limb being inturned toward and above said bearing edge to clamp said head and body portions thereagainst.

In testimony whereof I hereunto set my hand in the presence of two witnesses.

FORÉE BAIN.

In the presence of—
W. LINN ALLEN,
MARY F. ALLEN.
